CLAIM

The ornamental design for a motor vehicle, toy replica, and/or other replica as shown and described.

DESCRIPTION

FIG. 1 is a left, front perspective view of a motor vehicle, toy replica, and/or other replica according to the design;

FIG. 2 is a left, rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top view thereof.

Portions of the motor vehicle, toy replica, and/or other replica shown in broken lines form no part of the claimed design.

1 Claim, 7 Drawing Sheets
